Inventor:
Samuel P. Jenks

United States Patent Office.

LEMUEL P. JENKS, OF BOSTON, MASSACHUSETTS, ASSIGNOR TO HIMSELF
AND AARON KINGSBURY, OF SAME PLACE.

Letters Patent No. 102,943, dated May 10, 1870.

IMPROVED BREAD-MACHINE.

The Schedule referred to in these Letters Patent and making part of the same.

To all whom it may concern:

Be it known that I, LEMUEL P. JENKS, of Boston, Suffolk county, State of Massachusetts, have invented a new and improved Machine for Mixing and Kneading Bread and other substances; and I do hereby declare that the following is a full and exact description of the same, reference being had to the accompanying drawings, with letters of reference marked thereon.

In the drawings—

Figure 1 is a side view of my machine, and
Figure 2 is a view from the top.

Figure 3 is a perspective view, diminished from convex side, of part of plate K and plate-scraper L, pan C C, and cross-bar H.

And in the drawings—

A A, figs. 1 and 2, represent a platform, made of two pieces of wood crossing each other at right angles.

B B, fig. 1, are two upright standards fastened to the platform.

C C, figs. 1 and 2, show a tin pan resting upon and fastened to the rotating disk D. It is held by means of three horizontal loops, C C C, fig. 2, C, fig. 1, attached equidistantly to the sides of the pan, which loops receive three pegs bent at right angles, (see two of them in fig. 1,) which pegs are attached to the disk D, figs. 1 and 2, which has a bevel cog-wheel attached to it.

The axis of the disk is vertical, and it rotates by means of the shaft E, fig. 1, playing in a bearing in the center of the platform A A.

F, fig. 1, is a bevel cog-wheel, whose axis is horizontal. It is borne by the right-hand standard B, and a block attached to the standard serving as an additional bearing, and is rotated by the crank G, fig. 1, with its handle, seen in figs. 1 and 2.

From top of the standards B B passes a slab of wood, H, figs. 1 and 2, called "the cross-bar," hinged to the left-hand standard, and passing, by means of a tenon at its end, across the top of the other standard, where it is fastened in place by the peg I, figs. 2 and 1.

This cross-bar H bears, on its lower side, one side of its center, fastened to it by nuts and screws, two vertically-placed rods or wires, J J, figs. 1 and 2, to which is attached a metallic plate, K, figs. 1 and 2, called "the kneading-plate," curved, as seen from above, which plate, as seen in fig. 2, reaches horizontally from the center of the pan C C nearly to its periphery, and perpendicularly from the lower side of the cross-bar H nearly to the bottom of the pan C C.

The kneading-plate bears, firmly fixed to its inner curved side, a flat metallic bar, M, figs. 1 and 2, called the pan-scraper. This flat bar passes down nearly to the bottom of the pan, then proceeds, horizontally, close to the bottom of the pan, sometimes scraping it, till it reaches the side of the same, and then per-

pendicularly up as high as the top of the pan, and is there, at the side of the pan, so twisted that one edge impinges upon the side of the pan, while its horizontal section line forms a portion of a secant of the circle described by the periphery of the pan, (see fig. 2.)

L, fig. 1, (dotted lines fig. 2,) is a piece of wire, or a metallic rod, called "the plate-scraper," which is held by three ears projecting horizontally from the outside of the pan, in which ears it partially rotates with freedom, laterally. Proceeding vertically to a little above the top of the pan, it is bent at a right angle horizontally, proceeding to and a little beyond the center of the pan, being curved in its horizontal portion, as seen in fig. 2, to the same curvature with that of the kneading-plate. Having passed a little beyond the center of the pan it then proceeds perpendicularly downward to within a short distance of the bottom of the pan, where it terminates.

Between the two lower ears seen in fig. 1, this rod is squared, and bears, passing through it, by means of a square hole in the same, a plate, N, figs. 1 and 2, called "the spring-plate," which projects horizontally outward a short distance, and has at its outer end a hole which bears a spring, (India rubber or other,) O, fig. 2, passing horizontally to a hook, P, fig. 2, which is fastened to the outside of the pan.

Q, fig. 1, is a flat piece of iron, called "the fastener," hanging by the screw or bolt 3, from one end of one of the cross-pieces of the platform A A. It is perpendicular and then horizontal for a short distance, bearing in the latter part a thumb-screw R, fig. 1.

Imbedded in the end of the cross-piece of the platform, in a square cavity sunk therein, is a piece of rubber, U, fig. 1, called "the fastener-spring," and parallel with it, in the same cavity, is placed a piece of metal, T, fig. 1, of the same shape, called "the fastener-plate," which, by the resilience of the rubber fastener-spring, is pressed outward against the fastener, to hold it in any desired position. To assist this action I have a pin, V, fig. 1, projecting from the inner surface of the fastener toward the plate, and two countersunk holes in the fastener-plate, one opposite the pin, as shown in fig. 1, marked W.

And the operation of my device is as follows:

Placing the machine by the edge of a table, with the fastener in the position seen in the drawing, I screw up the thumb-screw R against the lower side of the table-edge. It is thus held firmly. Then, placing the flour, &c., or other substance or substances operated on, in the pan, I, by means of the crank G, rotate the disk D and its bevel cog-wheel, thus rotating the pan, whose contents are thus carried round till they encounter the outer or periphery edge of the kneader-plate K, and are then compressed between it and the inner side of the pan, mixing or kneading

them thoroughly. The cohesion of the substances attaching them to the convex side of the kneader-plate, they are removed by the plate-scraper L, which is held firmly to the kneader-plate by the contraction of the spring O. That portion of the substances operated on which coheres to the inside of the pan is removed by the pan-scraper M, and thrown again to the center of the pan. After the revolutions have continued a short time, the process of mixing or kneading is finished. I then remove the plate-scraper L and the peg I, and, raising the cross-bar H, lift the kneading-plate K from the pan. Turning the pan on its center to the right, in, I remove it from the disk D, and, if the substance operated on is bread, put it away to rise. Turning round the fastener Q, it is retained there by the device named, and my machine is then, with convenience, placed away upon a shelf or table.

And what I claim herein as of my own invention, and desire to secure by Letters Patent, is—

1. In bread and other mixing or kneading-machines,

the stationary plate or column (fixed to the cross-bar above,) extending from near the center of the pan to very near the periphery of the same, in combination with a rotating pan, all substantially as described.

2. The plate or cylinder-scraper L, actuated by the lever-plate and spring, and rotating round a stationary plate or column, and passing between the same and the periphery of the pan, all substantially as described.

3. The combination of the plate-scraper L with the stationary plate or column K, for the purpose above named, all substantially as described.

4. The above-described clamp or fastening Q, in combination with the bread-machine above described, all substantially as stated.

5. The general combination and arrangement of the whole machine, all substantially as described.

LEMUEL P. JENKS.
